(57) **CLAIM**

The ornamental design for a snap-lock construction toy robot, as shown and described.

DESCRIPTION

FIG. 1 illustrates a front, top, and right side perspective view of a snap-lock construction toy robot according to one exemplary embodiment of the present invention.

FIG. 2 illustrates a rear, bottom, and right side perspective view of the snap-lock construction toy robot according to the embodiment of FIG. 1.

FIG. 3 illustrates a top elevation view of the snap-lock construction toy robot according to the embodiment of FIG. 1.

FIG. 4 illustrates a bottom elevation view of the snap-lock construction toy robot according to the embodiment of FIG. 1.

FIG. 5 illustrates a rear elevation view of the snap-lock construction toy robot according to the embodiment of FIG. 1.

FIG. 6 illustrates a front elevation view of the snap-lock construction toy robot according to the embodiment of FIG. 1.

FIG. 7 illustrates a left side elevation view of the snap-lock construction toy robot according to the embodiment of FIG. 1; and,

FIG. 8 illustrates a right side elevation view of the snap-lock construction toy robot according to the embodiment of FIG. 1.

The broken line structures provided in the Figures illustrate environmental structures that form no part of the claimed design.

1 Claim, 8 Drawing Sheets
